The dominant features of my design reside in those portions shown in full lines on the drawing and is characterized by the peripheral insets adjacent the top and base of the desk in combination with the panel creating vertical insets on the rear of the desk, all as shown.

I claim:

The ornamental design for a desk, substantially as shown and described.
